UNITED STATES PATENT OFFICE.

NICHOLAS W. MONTGOMERY, OF GLOUCESTER, MASSACHUSETTS.

UNDER-WATER EXHAUST FOR EXPLOSIVE AND OTHER ENGINES.

1,065,707.

Specification of Letters Patent.

Patented June 24, 1913.

Application filed August 7, 1912. Serial No. 718,703.

To all whom it may concern:

Be it known that I, NICHOLAS W. MONTGOMERY, a citizen of the United States, and a resident of Gloucester, in the county of Essex and State of Massachusetts, have invented an Improvement in Under-Water Exhausts for Explosive and other Engines, of which the following description, in connection with the accompanying drawings, is 5 a specification, like characters on the drawing representing like parts.

This invention relates to exhausts for explosive and other engines, and is particularly adapted for use as an under-water 10 exhaust for explosive engines employed in motor boats.

In order that the principle of the invention may be readily understood, I have disclosed a single embodiment thereof in the 15 accompanying drawing, wherein—

Figure 1 is a vertical view partially inside elevation and partially in vertical section of one embodiment or form of the invention; Fig. 2 is an underneath plan of the 20 discharge shoe; Fig. 3 is a vertical section upon the line 3—3 of Fig. 1 and looking toward the right in said figure; and Fig. 4 is a vertical section upon the line 4—4 of Fig. 1 and looking toward the left in said 25 figure.

Although my invention is adapted to various uses, I have herein disclosed the same as applied to an explosive engine used in a motor boat, inasmuch as the invention is 30 peculiarly adapted to such use. Although I shall describe the invention with special reference to such use, it is to be understood that it is in no respect limited thereto, but so far as certain features thereof are concerned, it is of general application.

Owing to the noise made by the exhausts of motor boats, the exhausts have been submerged, but, so far as I am aware, with the invariable result of decreasing the speed of 45 the boat. The exhaust herein disclosed not only does not decrease the speed of the boat, but it does away with all noise of exhaust, all odor, vibration, excepting that of the engine, and pounding upon the bottom 50 of the boat. I have been enabled, by employing the submerged exhaust herein disclosed, to drive the boat at a greater speed than when employing an open exhaust, without muffling.

Referring more particularly to the drawing, I have therein represented an exhaust chamber 1 of any suitable shape and construction whereinto the exhaust motive agent from the engine is admitted through the pipe 2. Herein I have represented the 55 pipe 2 as opening into the forward end of the exhaust chamber 1. While the size of the chamber 1 may be largely varied within the scope of my invention, I have obtained excellent results by making it of such size 60 that its capacity is substantially six times the capacity of the compression chamber of the gasoline or other explosive engine with which I preferably employ it.

At a suitable point with relation to the 65 pipe 2, I provide a baffle plate 3 herein represented as extending from the lower portion of the forward end 5 of the exhaust chamber 1 in an upward and rearward direction to a point 6 adjacent the top of said 70 exhaust chamber. The said baffle plate may be formed with the walls of the chamber or suitably attached thereto. The baffle plate 3 terminates below the top of the chamber 1 to permit the passage of the burnt gases 75 or other motive agent thereover and into the main portion 7 of said chamber. At a suitable point and preferably in advance of the baffle plate 3 I provide a pipe 8 for discharging a suitable fluid into the chamber 80 1 to reduce the temperature of the exhaust motive agent and partially, at least, to stop the expansion thereof. Preferably for this purpose I introduce the overflow or waste from the circulating water of the engine 85 employed to cool the latter. This water is discharged under pressure into the exhaust chamber 1 at any desired temperature and is there brought into intimate contact with the exhaust motive agent. To effect this result 90 most efficiently, preferably I spray the water, and for that purpose have herein represented a projection or shelf 9 extending rearwardly a substantial distance from the head 1 of the exhaust chamber and there terminating in an upwardly extended lip 10 provided with a series of perforations 11, wherethrough the water is sprayed toward and preferably against the baffle plate 3 and 95 into intimate association with the exhaust 100 passage.

The result of the introduction of the water in the manner described and its intimate

association with the exhaust motive agent is materially to reduce the temperature of the latter and to stop the expansion of said agent or largely to reduce the expansion thereof. The result of this action is such that there is no pressure within the chamber 1.

In order to secure the best results, the exhaust motive agent is discharged from the chamber 1 at a point substantially adjacent its point of admission thereinto, thus compelling the circulation of said agent about the chamber, as indicated by arrows in Fig.

1. In said figure, I have represented the discharge pipe 12 as communicating with the bottom of the exhaust chamber 1 at a point 13 close to the head 5 of said chamber and beneath the lower end of the baffle plate 3. Thus, the commingled exhaust motive agent and spray water or vapor are effectively circulated and eventually discharged as described.

The discharge is effected through some suitable part of the hull, and preferably through the bottom thereof. In Fig. 1, I have represented a portion of the bottom of the hull at 14 and have represented the pipe 12 as extending downwardly to the hull and there provided with a discharge shoe 15, herein represented as extending at a downward inclination through the hull and into the water. The shoe 15 is constructed as a short section of pipe having a discharge end 16 and a flange 17, by which it may be secured by screws 18 or otherwise to the bottom of the hull. The boat when moving forwardly moves in the direction of the arrow adjacent Fig. 1,—that is, toward the right viewing said figure. It will, therefore, be observed that the submerged portion of the shoe is of a general wedge shape, the heel of the wedge being at the rear, and preferably provided with a downwardly extending lip 19.

45. When the boat is moving forwardly, the inclined face 20 of said shoe 15 forces the water downwardly or away from said surface and it at once rises at the opposite sides 21, 22. In this action the lip 19 coöperates, 50. Therefore the shoe when moving forward forms a pocket or cavity in the water, this cavity being at any instant of time of comparatively small volume, but continuously moving forward with the boat. The exhaust motive agent discharged through the outlet 16 of the shoe is discharged directly into this pocket, and I have discovered that all noise of exhaust is eliminated, and that the speed of the boat is not reduced. I attribute this result to the formation of a partial vacuum or of a chamber or pocket in the water, whereinto air from the water enters, so that the exhaust motive agent is not discharged directly into the water but into an air pocket or partial vacuum. The result

in any case is to eliminate all noise of the exhaust and to drive the boat at a speed which is equal to or greater than that obtained from an open exhaust without a muffler.

70. It will be observed that the shoe 15 extends, preferably, but a slight distance below the bottom of the boat, and hence there is little or no danger that it will come in contact with rocks or other obstructions. 75. The lip 19, which I term a bubble rim, materially assists in causing the formation of the pocket.

75. The lip 19 constitutes an agitating projection which serves to facilitate the separation of air from the water by causing the formation of air bubbles. This separated air immediately passes into the pocket formed by the shoe 15 and thus aids in supplying air to the said pocket. The air thus received in said pocket assists in muffling the exhaust and materially reduces the noise thereof. The maximum efficiency of the lip is secured by forming it upon the inclined face 20 closely adjacent the discharge end 16. 80

85. The submerged or under-water exhaust operates to best advantage when the engine is on the direct, but will operate satisfactorily on the reverse, but the engine will be slowed down, because no pocket is formed. 90. By connecting the discharge pipe 12 at a point near the front end of the chamber 1, I effectually prevent the stoppage of the engine on the reverse, which would occur were the discharge pipe 12 connected directly to the rear end of the chamber 1, particularly if the baffle plate 3 were not employed. 95

100. The exhaust chamber 1 is represented as inside the hull, and preferably it is located back of the engine. The shoe 15 may and preferably does terminate at a point close to the hull, but within the scope of my invention may be extended downwardly or laterally to any desired length. 105

110. Although I have obtained the best results by spraying the water introduced through the pipe 8, it is not essential that this be done. In the event that I employ my invention in connection with a steam engine, 115 I preferably do not introduce any fluid through the pipe 8, but omit such feature of the invention.

120. I do not in this application claim the chamber 1 nor those features of the invention immediately co-acting therewith.

Having thus described one illustrative embodiment of my invention, I desire it to be understood that although specific terms are employed, they are used in a generic and descriptive sense and not for purposes of limitation, the scope of the invention being set forth in the following claims.

125. 1. An under-water exhaust for explosive or other engines comprising a shoe adapted 130

to project through the submerged portion of a boat's hull, said shoe comprising a pipe section having a rearwardly and downwardly inclined wall 20 terminating in an open discharge end 16 and having a downwardly directed lip 19 projecting angularly from the said inclined wall.

2. An under-water exhaust for explosive or other engines comprising a shoe adapted 10 to project through the submerged portion of a boat's hull, said shoe comprising a pipe section having a rearwardly and downwardly inclined, imperforate, deflecting wall 20 terminating in an open discharge 15 end 16 and having a terminal lip 19 extending substantially normal to said wall.

3. An under-water exhaust for explosive or other engines comprising a shoe adapted 20 to protrude through the submerged portion of a ship's hull, the protruding portion of said shoe consisting of a downwardly and rearwardly inclined wall 20 terminating in a downwardly directed angular lip 19, and 25 upright, substantially parallel side walls 21, 22 terminating forwardly in the plane of the face of said inclined wall, thereby per-

mitting immediate upward discharge of the water at the lateral edges of the wall 20.

4. An under-water exhaust for explosive or other engines comprising a shoe adapted 30 to project through the submerged portion of a boat's hull, said shoe having a rearwardly and downwardly inclined wall terminating in an open discharge end, and a water agitating lip.

35 5. An under-water exhaust for explosive or other engines comprising a shoe adapted to project through the submerged portion of a boat's hull, said shoe having a rearwardly and downwardly inclined wall and 40 a rearwardly and downwardly directed discharge outlet, and a water agitating lip projecting from said inclined surface closely adjacent the said discharge end.

In testimony whereof, I have signed my 45 name to this specification, in the presence of two subscribing witnesses.
